UNITED STATES PATENT OFFICE.

ERMANNO GALANTE, OF WOBURN, MASSACHUSETTS.

HIDE-STRETCHING DEVICE.

Application filed April 25, 1928. Serial No. 272,682.

The invention relates to an improvement in hide-stretching devices having a frame within which the hide is contained and by which the hide is secured and held stretched by fastenings on the frame to which strings connecting with the hide are secured.

Among the essential objects of the invention is to avoid the use of nails or tacks as a means of fastening for securing the hide strings to the frame and in place thereof to provide the frame with permanent fastenings for the hide strings which may be used again and again as long as the frame lasts.

A further object of the invention is to provide a fastening for the hide strings of simple construction; one that will admit of an easy fastening of the hide string or release of it; one that will admit of the hide string being highly tensioned for stretching the hide and will grip the string when thus tensioned and hold the tension without let-up or slipping, and especially to provide a fastening that cannot become gummed, inasmuch as the operative parts are concealed or housed within the frame.

The invention can best be seen and understood by reference to the drawings, in which—

Figure 1 is a plan of the improved hide-stretching device showing the frame equipped with the various hide string fastenings, to which the invention especially pertains.

Fig. 2 is a section on the line 2—2 of Fig. 1.

Fig. 3 is a side elevation of a portion of one of the frame bars equipped with two of the fastenings and attached hide strings, one of the fastenings being shown with the head 40 of the bolt, to which special reference will later be made, removed, and

Fig. 4 shows partly in section and partly in side elevation a slightly modified construction to which special reference will later be made.

Referring to the drawings:—

1 represents the frame preferably rectangular in form as are also its several bars. According to the embodiment of the invention shown in Figs. 1 to 3, inclusive, the frame is of wood as distinguished from a metal frame. Located within the frame is the hide or leather 2 to be held stretched. Secured to the hide at spaced points around the edge thereof are strings 3 through which the hide is fastened to the frame. Secured to the in-

ner ends of each of these strings are toggles 4 by which the attachment of the strings to the hide is secured in the usual manner. The outer ends of the strings are secured to the several bars of the frame and the strings held taut and the skin thereby stretched by permanent fastenings 6 on the frame, which fastenings form the essential subject-matter of the invention.

The fastenings 6 are arranged upon the several bars of the frame preferably at periodically spaced distances from one another and preferably such number of fastenings are employed as will accommodate a hide or skin having a maximum number of attaching strings. The fastenings 6 are made as follows: For the purpose of obtaining an initial setting for each fastening the frame is provided with a hole or opening 7 extending through the outer side or face of the frame to and through the inner side or face thereof. This hole or opening is prepared by a boring in the frame. The preparation of the hole or opening 7 through the frame is also such as to provide an interior shoulder or edge 8 within the frame. This shoulder or edge is prepared by making that portion 9 of the opening which passes through that portion of the frame adjacent its outer face of smaller diameter than that portion 10 of the opening passing through the inner side or face of the frame. Extending into the opening 7 in the frame is a bolt 11 having a head 12 and a shank 13, the outer end 14 of which is made threaded. The bolt is extended into the opening from the outer side of the frame so that the head of the bolt will draw against the outer side or face of the frame at which point the frame is preferably provided, when of wood, with a socket 15 into which the head may draw. The shank of the bolt is preferably of a diameter slightly less than the portion 9 of the hole in the frame through which it extends so as to have an easy sliding fit therein. The extension of the bolt is preferably such that its inner end will lie within the enlarged portion 10 of the opening in the frame inside the inner side or face thereof when the head of the bolt is seated against the outer side or face of the frame as aforesaid.

Arranged upon the threaded end 14 of the bolt in extension of it is an end-piece 16 in the nature of a cap. This end-piece when in place projects into the enlarged portion 10 of

the opening in the frame and presents inside the opening an edge or shoulder 17 which is opposed to the edge or shoulder 8 on the frame. The endpiece is of slightly less diameter than the opening 10 in which it is contained in order that it may have an easy sliding fit therein. The extension of the endpiece 16 from the inner end of the bolt is such that when the bolt is positioned with 10 its head bearing against the outer side or face of the frame, the endpiece on the inner end of the bolt will then project inward some little distance beyond the inner side or face of the frame.

15 Arranged upon the bolt within the enlarged portion 10 of the opening through the frame, with bearing at one end against the shoulder or edge 8 of the frame and at its other end against the shoulder or edge 17 presented by the inner end of the endpiece, is a coiled tension spring 18. In the assembling of the fastening the bolt is first passed from the outer side through the opening 7 in the frame with the inner end portion of the bolt contained within the enlarged portion 10 of the opening. The spring 18 is then placed upon the inner projecting end of the bolt by insertion through the opening 10 from the inner side of the frame. The endpiece is then applied to the threaded end of the bolt by insertion into the opening from the inner side of the frame. As the endpiece is then screwed or tightened onto the inner end of the bolt it will operate 35 to tension the spring which then becomes tensioned between the opposing edges or shoulders 8 and 17 on the frame and endpiece respectively and the spring thus tensioned will then normally operate to hold the head of the bolt hard pressed against the outer side or face of the frame.

Assuming the hide to be placed within the frame, the operations of securing any one 45 of the various attached strings to any one of the adjacent fastenings on the frame is initially obtained by pressure of the finger applied to the endpiece 16 of the fastening. This pressure acts through the bolt, the spring 18 then becomes compressed to displace the head of the bolt away from the outer side or face of the frame, the shank of the bolt adjacent the head then becoming exposed. The string is then wrapped around the exposed portion of the shank with 50 one or more windings and then the endpiece is released and the head will be drawn by the spring forcibly against the frame, thereby holding the end of the string securely in place, and when the outer side or face of the frame is provided with a socket into which 55 the head draws, the end of the string will be held by the head within this socket. For releasing any one of the strings the head of the bolt is displaced by pressure on the endpiece the same as before and the string then

unwrapped and released from the fastening. To prevent fraying of the strings by drawing over the sharp corner edges of the frame their edges adjacent each fastening is provided with a cutout or groove 20.

70

In Fig. 4 a slight modification is shown in that the frame is not of wood but of metal piping which might well be used in the present connection. The structure is almost precisely the same as in the case of a 75 wooden frame. Borings are formed in the piping which correspond with the borings in the wooden frame and the relation of the bolt and other operating parts is precisely the same, all the parts being numbered the 80 same as with the wooden frame, the only exception being that no socket is provided with the piping for receiving the head of the bolt when seated.

85

Having thus fully described my invention, I claim and desire to secure by Letters Patent of the United States:—

1. In a hide-stretching device of the type specified having a frame in which the hide is stretched by strings attached to the hide 90 connected to the frame, fastenings for securing the strings to the frame, said fastenings comprising shanks slidable within openings in the frame and heads carried by the shanks having drawing engagement with the side 95 of the frame or outward displacement therefrom as the shanks are moved, and tensional means functioning to hold said heads in normal drawing engagement with the side of the frame but with permitted outward 100 displacement therefrom as aforesaid whereby on displacement of said heads said strings may be wound around the then exposed shanks and afterward held bound between the heads and the frame as the heads are allowed to resume their normal drawing engagement therewith as aforesaid.

105

2. In a hide-stretching device of the type specified having a frame in which the hide is stretched by strings attached to the hide and connected to the frame, fastenings for securing the strings to the frame comprising bolts having shanks passed through openings in the frame and slidable therein and heads having drawing engagement with the side of the frame or outward displacement therefrom as the bolts are moved, and means associated with each one of said bolts inside the frame functioning to exert tension thereon for holding the head of the bolt in normal drawing engagement with the side of the frame but with permitted movement of the bolt and outward displacement of the head thereof as aforesaid.

110

3. In a hide-stretching device of the type specified having a frame in which the hide is stretched by strings attached to the hide and connected to the frame, fastenings for securing the strings to the frame comprising bolts having shanks passed through openings 115

120

125

130

in the frame and slidable therein and heads having drawing engagement with the side of the frame or outward displacement therefrom as the bolts are moved, means associated with each one of said bolts inside the frame functioning to exert tension thereon for holding the head of the bolt in normal drawing engagement with the side of the frame but with permitted movement of the bolt and outward displacement of the head thereof as aforesaid, and means whereby said bolt may be moved and outward displacement of its head obtained as aforesaid by application of pressure to the inner end of the bolt from outside said frame.

4. In a hide-stretching device of the type specified having a frame in which the hide is stretched by strings attached to the hide and connected to the frame, fastenings for securing the strings to the frame comprising bolts having shanks passed through openings in the frame and slidable therein and heads having drawing engagement with the side of the frame or outward displacement therefrom as the bolts are moved, tensional means inside the frame associated with each one of the bolts for normally holding the head thereof in drawing engagement with the side of the frame but permitting movement of the bolt and outward displacement of its head away from the side of the frame as aforesaid, and means connecting with the inner end of the shank of each bolt whereby the shank may be moved and outward displacement of its

head obtained from a point outside but adjacent that side of the frame opposite the side against which the head has normal bearing.

5. In a hide-stretching device of the type specified having a frame in which the hide is stretched by strings attached to the hide and connected to the frame, said frame having spaced openings through it, each of said openings being larger in cross section in the part adjacent one side of the frame than in the part adjacent its opposite side, leaving a shoulder inside the frame between said portions of the opening, bolts having shanks extending into the respective openings in the frame and slidable therein and heads on the shanks having drawing engagement against that side of the frame adjacent that portion of the opening therethrough having the lesser cross section, endpieces having threaded connection with the inner ends of the bolts in extension thereof, said endpieces being contained in those portions of said openings having the larger cross section and extending through and beyond that side of the frame opposite the side against which the heads of the bolts have bearing, and springs arranged upon the shanks of the respective bolts inside the frame, each of the springs being tensioned between one of the shoulders on the frame and the inner opposing end of the endpiece of the shank on which the spring is arranged.

ERMANNO GALANTE.
